UNITED STATES PATENT OFFICE.

ROBERT L. DARRAGH, OF NEW YORK, N. Y.

WATER-FILTER.

SPECIFICATION forming part of Letters Patent No. 356,242, dated January 18, 1887.

Application filed June 24, 1886. Serial No. 206,127. (No model.)

To all whom it may concern:

Be it known that I, ROBERT L. DARRAGH, of the city, county, and State of New York, have invented a new and useful Improvement in Water-Filters, of which the following is a full, clear, and exact description.

My invention consists in the construction and combination of parts, as will be hereinafter fully described and claimed.

Reference is to be had to the accompanying drawings, forming a part of this specification, in which similar letters of reference indicate corresponding parts in both the figures.

Figure 1 represents a vertical section of a water-filter embodying my invention; and Fig. 2, a transverse section, on a reduced scale, upon the irregular line $\alpha\alpha$ in Fig. 1.

A A' indicate the body of the filter, forming or constituting upper and lower chambers, the one, 20 A', of which is made in two vertical sections or halves united by flange-joints a a , and is fitted with a perforated cross-plate or diaphragm, b , upon which the sand, charcoal, or other filtering material c is placed, said plate resting upon 25 an inner flange or lugs, d . The upper body portion, A, is made in a single piece, and is united to the lower body part, A', by a flange-joint, a' . This construction of the body is not only a convenient one as regards putting the 30 filter together, but affords every facility for inserting and replacing when necessary the filtering material and perforated diaphragm.

The space above the diaphragm b constitutes the filter proper and chamber in which the filtered water collects, and the space below said diaphragm the sediment-chamber. The chamber A is provided at or near its top with a delivery-pipe controlled by a cock or valve, e , and the chamber A' is similarly constructed or 40 provided with a lower outlet or extension fitted with a cock or valve, f . This extension forms part of the sediment-chamber, and should be of considerable depth above the valve f to hold the deposit or collecting sediment.

45 D is the water-supply pipe of the filter, fitted with a cock or valve, g , and which may be connected with the service-pipe of a water-main or be otherwise connected to supply water under pressure. This pipe D is fitted to 50 enter the chamber A', and is connected to or provided at its discharge end with a cup-like

spreader, S, having a perforated top disposed to occupy a position in the upper portion of the chamber A' at a short distance below the perforated diaphragm b , so as to deliver the supply-water in a series of upward jets against the under surface of the perforated diaphragm b , and to leave a clear enlarged space outside of the spreader and below it for the collection of the sediment. The top or cover of the spreader is preferably of convex form, and is fitted or provided with a series of raised nipples, h , where perforated for the supply-water to issue in jets through. The object of this construction will be hereinafter explained.

In the operation of the filter, when the supply and delivery cocks g e are opened the supply-water entering the spreader S has its force or violence broken by the resistance which said spreader and its extended top present to it, and this, combined with the effect produced by the combined area of the perforations in said top being in excess of the area of the supply-pipe, causes the supply-water to ooze or flow in a series of gentle jets up through the perforated top or nipples h to and through the filter proper or perforated bottom b of the filtering-chamber and filtering material thereon, without agitating the water within the lower sediment-chamber or disturbing the impure matter or sediment collected in said chamber and carrying such matter or sediment into the filtering material to foul it. Only the incoming water passes to be filtered, and after being filtered escapes through the delivery faucet or cock, the water within the portion of the chamber A' below the spreader or its upper surface not being agitated by the incoming water, but remaining quiescent, thus not fouling the supply-water as it is distributed over the under area or surface of the perforated diaphragm b and up through the filtering material c .

The spreader S should be of sufficient capacity and of such enlarged area on its perforated top, near the under surface of the filtering material or perforated plate b , to insure a thorough distribution and free but gentle discharge of the supply-water over the whole bottom area of the filtering-surface without disturbing the impure matter or sediment in the main or lower portion of the chamber A'.

The nipples h serve to discharge the supply.

water in gentle and easy jets without disturbing the water lying on top of the spreader, while the convex form of the top of the spreader establishes a series of inclined courses or channels for any water-holding sediment on said top to slip or pass off quietly along with the sediment which it carries to the space below the spreader.

When necessary, the water and sediment in the chamber A' are discharged by opening the cock f, which will cause the water in the upper chamber, A, to descend and clean the filter.

Having thus fully described my invention, I claim as new and desire to secure by Letters Patent—

In a water-filter constructed to operate as described, the perforated spreader S, of convex form on its top, and provided with upwardly-projecting nipples h, in combination with the supply-pipe D, the upper filtering and lower sediment chambers of the filter, and their dividing perforated diaphragm b, substantially as specified.

ROBERT L. DARRAGH.
